(57) CLAIM

The ornamental design for a wine rack, as shown and described.

DESCRIPTION

FIG. 1 is a front perspective view of the wine rack;

FIG. 2 is a left side view of the wine rack;

FIG. 3 is a right side view of the wine rack;

FIG. 4 is a rear view of the wine rack;

FIG. 5 is a front view of the wine rack;

FIG. 6 is a bottom view of the wine rack;

FIG. 7 is a top view of the wine rack; and,

FIG. 8 is a front view of the wine rack, with a pair of wine bottles (shown in phantom) inserted in the wine rack, which wine bottles do not form a part of the claimed design.

The broken line showing of a wine bottle in FIG. 8 is included for the purpose of illustrating only and forms no part of the claimed design.
